UNITED STATES PATENT OFFICE

CHARLES S. WILLIAMS, OF KINGSTON, PENNSYLVANIA, ASSIGNOR TO ELECTRIC SERVICE SUPPLIES COMPANY, OF PHILADELPHIA, PENNSYLVANIA, A CORPORATION OF PENNSYLVANIA

APPARATUS FOR AND METHOD OF DEVELOPING HIGH VOLTAGE DIRECT CURRENT SUPPLY

Application filed August 31, 1928. Serial No. 303,133.

This invention relates to improvements in electric generators of the direct current type such as are used to furnish current for locomotive head-lighting, and more particularly to an apparatus for and method of utilizing the direct current armatures of such generators for developing a high voltage direct current supply for various automatic train control and train stop systems.

Heretofore and prior to this invention, the high voltage direct current plate circuit supply to the amplifiers of the various automatic train control and train stop systems now in use has been developed by a dynamotor driven by the headlight generator. For ordinary locomotive head-lighting, train lighting and the like, turbo-generators have been used which generate direct current at 32 volts. In order, however, to supply the plate circuit of the train control and train stop systems with direct current at 300 or more volts, it has been necessary to employ a high voltage battery or a dynamotor which is driven by the turbo-generator and which operates to convert the 32 volts generated by the latter to the 300 or more volts required for automatic train control operation.

It is among the principal objects of this invention to provide an apparatus for and method of developing a high voltage direct current supply, the source of which is derived directly from the commutator of the usual headlight generator to thereby avoid the necessity for using dynamotors or high voltage batteries.

More specifically, it is an object of this invention to provide the headlight generator with an auxiliary set of current collecting rings electrically associated with the generator commutator in such manner as to permit an alternating current to be collected from the direct current armature of the generator, in combination with means for increasing the alternating current voltage so obtained for subsequent rectification for use in connection with various automatic train control, train stop and locomotive and train communication systems.

Other objects, features and advantages of the present invention will appear more fully

hereinafter, it being understood that the invention consists substantially in the combination, construction, location and relative arrangement of parts, all as will appear more fully hereinafter, as shown in the accompanying drawings, and as finally pointed out in the appended claims. The invention has been shown and described, for purposes of illustration only, in connection with what is generally known as the two-speed, single element, continuous, inductive, automatic train control system. It will, of course, be understood that the present invention is applicable to any type of train control or communication system and is not limited to the particular system herein shown for the purpose of illustrating the invention.

In the accompanying drawings:

Figure 1 is a diagrammatic view illustrating the present invention as embodied in the locomotive circuit of one form of train control system, the arrangement shown being adapted to give half wave rectification of the alternating current voltage;

Figure 2 is a diagrammatic view illustrating a somewhat modified form of the present invention for obtaining full-wave instead of half-wave rectification of the stepped-up alternating current voltage;

Figures 3 and 4 are diagrammatic views showing respectively the locations at which connections to the current collecting rings are made for commutators of two and four pole armatures.

Referring to the drawings and more particularly to Figure 1 thereof, it will be seen that I have shown my invention as being incorporated in that form of train control system known as the two-speed, single element, continuous, inductive, automatic train control. Inasmuch as the principles of this system are more or less well known in the art, it is not believed necessary to describe in detail the circuit shown in Figure 1 except in so far as my invention is associated therewith.

It will be observed that in the illustrated system, a two-stage amplifier is used which includes the tubes 10 and 11. In response to energization of the track receiver 12, the out-

put from the second stage amplifying tube 11 is delivered to the primary of the transformer 13. The alternating current which is delivered from the secondary of this transformer 13 is rectified by a rectifier designated generally by the reference numeral 14, the direct current thus obtained being employed to energize the direct current train control relay 15 of any suitable type. The remaining 10 elements of the illustrated train control system need not be described herein inasmuch as they form no part of the present invention, nor is their description necessary in order to explain my invention.

15 Heretofore and prior to this invention, it has been the more or less usual practice to supply the plate circuit of the amplifier by means of a dynamotor driven by the headlight generator. In some instances, the relatively 20 high voltage for the amplifier plate circuits was supplied from a high voltage battery. It is the purpose of this invention to replace the heretofore used dynamotors and high voltage batteries by a high voltage direct current 25 source which is obtained from the direct current armature of the turbo-generator, this generator being that which is ordinarily employed for supplying the necessary energy for locomotive head-lighting, train lighting 30 and the like.

In order that this purpose may be accomplished, I have provided the usual turbo-generator designated generally by the reference numeral 16 with a pair of auxiliary current 35 collecting rings 17. These current collecting rings 17 are suitably mounted upon the armature shaft 18, said rings being insulated from the shaft and from each other. The commutator 19 is also carried upon the shaft 18 in the 40 usual manner, the current collecting rings 17 being arranged adjacent the outer end of the commutator.

Figures 3 and 4 show in diagrammatic manner the connections between the collector rings 17 and the commutator segments 19. In the case of a two pole generator, the collector rings 17 are connected to segments of the commutator 19 arranged 180 degrees apart as measured about the circumference of the 50 commutator (see Fig. 3). In the case of a four pole generator, the current collecting rings 17 are electrically connected to segments of the commutator arranged 90 degrees apart as measured about the circumference of the 55 commutator (see Fig. 4). The turbo-generator 16 when so equipped with a commutator 19 and the current collecting rings 17 is capable of generating a direct current voltage and an alternating current voltage. In steam 60 train operation, the direct current voltage is ordinarily 32 volts as measured across the brushes 20 of the commutator. As has already been explained, the energy for the usual engine equipment, such as locomotive head- 65 lights and the like, is obtained from the com-

mutator of the generator. The energy for the amplifier plate circuits used in connection with automatic train control, train stop, and communication systems, is obtained from the current collector rings as follows:

Connected to suitable brushes 21 in electrical engagement with the current collecting rings 17 are the conductors 22, these conductors 22 being in turn connected to the primary terminals of a high impedance step-up 70 transformer 23. One terminal of the secondary coil of the transformer is connected to the common wire C of the amplifier, while the opposite terminal of the secondary coil of the transformer 23 is connected to the anode of a rectifying tube 24, in this instance a half wave non-filament rectifying tube. It will, of course, be understood that any other suitable type of rectifier may be employed. The cathode of the rectifier 24 is in turn connected to the plate reactors 25 of the amplifier. Preferably, a condenser 26 is connected across the leads on the load side of the rectifier 24 to smooth out the direct current. If desired, a suitable reactance (not shown) may 80 be employed in connection with the condenser 26 for straightening out the direct current.

From the foregoing, it will be apparent that I have provided an arrangement whereby by alternating current may be collected from 90 the direct current armature of a turbo-generator, the alternating current voltage so obtained being increased through the step-up transformer 23 for subsequent rectification by means of the rectifier 24. It will be observed that both the primary and secondary coils of the transformer 23 are provided with suitable taps for varying the range of the direct current voltage supply for the plate circuit of the amplifier. By means of these 100 taps, it is possible to obtain a plate circuit supply the range of which varies between 125 and 450 direct current volts.

Should it be desired to obtain full wave rectification in place of the half wave rectification hereinbefore described, it becomes merely necessary to substitute for the half wave rectifying tube shown in Figure 1 the full wave rectifying tube 27 shown in Figure 2. In the latter instance, the rectifier is provided with two anodes which are respectively connected to the secondary terminals of the transformer 23. The cathode of the full wave rectifier 27 is connected to the plate reactors of the amplifier exactly as in the former instance. The common wire of the amplifier is, however, in this instance connected to the mid-point of the transformer secondary (see Figure 2). As in the arrangement shown in Figure 1, a condenser is preferably shunted across the wires respectively leading to the plate reactors and to the common wire C of the amplifier, this condenser being arranged on the load side of the rectifier. A suitable reactance (not shown) may 120 125 130

be employed for straightening out the direct current.

It will be observed that in both of the arrangements hereinbefore described, the direct current voltage supply which is delivered by the commutator 19 of the headlight generator is not interfered with in any manner, the result being that there is simultaneously obtained from the same turbo-generator a low voltage direct current and a high voltage direct current. The necessity for using a separate dynamotor or separate high voltage batteries, in addition to the usual headlight generator, for supplying high voltage to various automatic train control and train stop systems and also for communication systems as are used on locomotives and trains is thus entirely obviated.

It will be understood, of course, that the invention is applicable for use in connection with any form of automatic train control and train stop system, as well as in connection with any form of communication system for use on locomotives and trains, the system herein disclosed being intended merely to illustrate one manner of applying the invention. It will be further understood that various changes may be made from time to time without, however, departing from the general spirit or principles of the invention, and it is accordingly intended to claim the invention broadly, as well as specifically, as indicated in the appended claims.

What is claimed as new and useful is:

35 1. In the locomotive circuit of an automatic train control system, in combination, an amplifier, locomotive control apparatus, a direct current generator having a single commutator for delivering low voltage current to said apparatus and to the filament circuit of said amplifier, a pair of collector rings operatively associated with said single commutator of the generator, a transformer having its primary terminals connected to said 40 rings for developing a relatively high alternating current voltage directly from said commutator and a rectifier included in the secondary circuit of the transformer for rectifying the alternating current voltage, the 45 terminals of said secondary circuit being respectively connected to the plate reactors of the amplifier and the common wire of the locomotive circuit.

2. In the locomotive circuit of an automatic train control system including control signalling apparatus requiring relatively low direct current voltage, in combination, an amplifier including filament and plate circuits, a direct current generator having a 50 single commutator, a pair of brushes operatively associated with said commutator for delivering the required direct current voltage to said locomotive control signalling apparatus and to the filament circuit of said 55 amplifier, a pair of collector rings operative-

ly associated with said single commutator of the generator for deriving alternating current therefrom, a transformer having the primary terminals thereof respectively connected to said rings, said transformer being 60 adapted to develop a relatively high alternating current voltage, and rectifying means included in the secondary circuit of the transformer for rectifying the alternating current voltage delivered by the transformer, the 65 cathode of said rectifying means being connected to the plate reactors of the amplifier with the secondary coil of said transformer connected in series between the anode of the rectifying means and the common wire of the 70 locomotive circuit, one of said commutator brushes being also connected to said common wire.

In testimony whereof, I have hereunto affixed my signature.

CHARLES S. WILLIAMS.
